UNITED STATES PATENT OFFICE.

WILLIAM G. KENDALL, OF NEWARK, NEW JERSEY.

VANITY CASE.

1,417,383.

Specification of Letters Patent. Patented May 23, 1922.

Application filed July 22, 1918. Serial No. 246,213.

To all whom it may concern:

Be it known that I, WILLIAM G. KENDALL, a citizen of the United States, residing at Newark, in the county of Essex and State 5 of New Jersey, have invented certain new and useful Improvements in Vanity Cases, of which the following is a specification.

This invention relates to improvements in vanity cases and more particularly to that 10 type which are designed to contain two dissimilar cosmetics such for example as, in the present instance, a cake of rouge and a cake of face powder.

One of the primary objects of the present 15 invention is to provide an article of this class so constructed that the two cosmetics will be housed in separate and distinct compartments and in such manner that they are equally accessible and either may be made 20 use of without exposing the other so that when one of the cosmetics is being employed there is no likelihood of loss or waste of the other cosmetic or of the puff or other applying means provided in connection 25 therewith.

Another object of the invention is to provide, in an article of this class, a common supporting means for the two cosmetics, as for example the face powder and rouge, 30 cakes as in the herein illustrated embodiment of the invention so that the article will be compact in form and considerable material may be saved in its manufacture.

The invention has as a further object to 35 provide a vanity case comprising two compartment members, and a supporting member arranged between the compartment members and designed to support upon its opposite faces the holders for the two cosmetics, the compartment members being so 40 connected that either may be swung to open position to expose the respective cosmetic housed therein, the said supporting member constituting at such time a closure for the 45 other compartment and serving therefore to effectually protect the cosmetic not being at that time employed.

The invention also has as its object the provision of a novel hinge connection common 50 to both of the compartment members and the supporting member so that by a single hinge all of the members are so connected that, as stated above, either compartment member may be swung to open 55 position for access to the respective cosmetic and the supporting member will at such time

remain in position closing the other compartment.

A still further object of the invention is to so relatively arrange and so connect the compartment members and the supporting member that when the article is entirely closed, the supporting member will serve the further purpose of a partition dividing the compartment members to effectually prevent mixing or intermingling of the cosmetic materials as for example by the sifting of any loose powder from one cake into the compartment containing the other cake and on to the said other cake.

While within the purview of the present invention the supporting member may be constructed or designed to support various kinds of cosmetics or various shapes and designs of holders for cosmetics, it is designed 75 in the herein illustrated and described embodiment of the invention as adapted for the support of pads for holding cakes of face powder and rouge, and it is a further object of the invention to provide a novel arrangement of holding fingers struck up from the body of the supporting member at the opposite sides thereof, the arrangement being such that a cake holding pad may be disposed upon each side or face of the said 80 member and frictionally and yet firmly retained in place by the resiliency of the fingers.

A further object of the invention is to strike up additional fingers to project from 90 the opposite faces of the supporting member and of greater height than the first-mentioned fingers so that they will project above the surface of the respective cosmetic tablet and in this manner serve as retaining fingers 95 for a powder puff or like applying device disposed upon the face of the tablet. Incidentally the invention contemplates that these retaining fingers shall constitute means for preventing lateral displacement of the 100 puff or like applying device to prevent accidental dropping of the same when the respective compartment member is swung to open position and also to prevent interference of the puff or the like with closing of 105 the respective compartment member as for example by displacement to project between the two compartment members in the act of swinging the same to closed position upon their hinge.

A still further object of the invention is to provide the supporting member with a

tongue located opposite the hinge connection for the compartment members and the supporting member and projecting interiorly of the article so that it may afford means for holding it in position to close either compartment member while the other is being swung to open position.

In the accompanying drawings:

Figure 1 is a perspective view of the vanity case embodying the present invention, the same being completely closed;

Fig. 2 is a similar view illustrating the same opened to expose for use one of the cosmetics;

Fig. 3 is a vertical front to rear sectional view through the case closed;

Fig. 4 is a group perspective view illustrating the several members of the case disconnected.

As before stated the vanity case embodying the present invention includes two compartment members, a supporting member positioned between the compartment members, and a common hinge connection between all of said members, and in the drawings one of the compartment members is indicated in general by the numeral 1 and the other by the numeral 2. Each of these compartment members comprises a wall 3 which may be cylindrical or of any other desired contour, and a wall 4. The walls 4 of the compartment members constitute, of course, closed tops for the members and, if the said walls 4 are flat, the wall of either member may serve as the base for the article when the article is disposed upon a dresser top or similar supporting surface. If desired, however, the said wall 4 of one of the compartment sections may be outwardly bulged or rounded as shown in the drawings so as to improve the appearance of the article, and this will particularly be true where each compartment member bears upon its exterior surface the name of the cosmetic contained therein. The hinge connection between the compartment members and the supporting member will be presently specifically described and it will, of course, be understood that due to the provision of this connection, the compartment members may be swung together so as to completely close the case or either compartment member may be swung upwardly or to open position while the other compartment member remains substantially stationary. In order to provide a relatively close fit between the compartment members when they are closed, the member 2 is preferably provided at the upper edge of its wall 3, and interiorly, with a substantially annular rim 5 which projects above the said upper edge of the wall and which fits within the open end of the member 1 when the members are closed as stated. In order to prevent accidental opening of the members, it is preferable that one or more small pro-

tuberances 6 be stamped in the rim 5 to project from the outer surface thereof and these protuberances are designed to snap into small sockets 7 formed in the inner surface of the wall 3 of the said compartment member 1. Thus when the compartment members are completely closed, the case will be sealed against the entrance of dust, and the perfumed cosmetics will better retain their strength and will be prevented from deterioration, or the disintegration of the tablets into powdered form.

The supporting member heretofore referred to is indicated in general by the numeral 8 and this supporting member is in the nature of a substantially circular sheet metal plate of a diameter to adapt it to be received more or less snugly within the circumference of the rim 5. In order to provide one member of the hinge connection between the compartment members and the supporting member, the said supporting member is formed at its periphery with a short outward extension 9 occupying the same plane as the body of the supporting member and in turn formed with a short and relatively narrow neck 10 provided with integral laterally projecting pintle studs 11 which extend in opposite directions from the said neck. As before stated the rim 5 is substantially annular but this rim is either cut-away or entirely broken at the point where the member 2 is to be hingedly connected with the members 1 and 8, and a portion of the wall 3 of the member 2 is formed with short spaced incisions and is bent outwardly as at 12, and at its outer edge has spaced portions rolled to provide pintle lugs 13. In a like manner the wall 3 of the member 1 is formed with spaced incisions and portions of the wall between the incisions is bent outwardly as at 14 and formed with pintle lugs 15. The neck 10, the lugs 13, and the lugs 15 are so relatively proportioned and spaced that when the lugs 13 and 15 are bent up about the pintle studs 11 in the manufacture of the article and in completing the hinge connection, the said lugs 15 will lie immediately at the opposite sides of the neck 10 and will, of course, extend around the inner ends of the studs 11, and the lugs 13 will extend around the said studs 11 immediately outwardly of the lugs 15. In this manner without the employment of any rivets, solder, or other disfiguring means or devices the three members 1, 2 and 8 are permanently and securely hingedly connected, and even more securely than if a separate pintle pin were substituted for the lugs 11 as is the usual construction in hinges of this general type. It will now be evident that the compartment members 1 and 2 may be selectively and independently swung to open and closed position, and that the supporting member 8 may also be swung upon the hinge connec-

- tion above described, when either or both of the compartment members are in open position. It will also be evident that the extension 9 of the supporting member 8 substantially fills and closes the space resulting from the formation of the portions 12 and 14 so that the presence of the hinge does not impair the substantially air-tight sealing of the case when closed.
- 10 As before stated the supporting member 3 is constructed to support upon each of its faces a cosmetic or a holder for cosmetic such for example as, in the present instance, a pad for holding a cake of face powder or rouge, the said member 8 serving, when either compartment member is swung to open position, the further purpose of a closure for the other compartment member, and in order that the said supporting member 8 may be held in the desired definite position while either compartment member is being swung to open position, and also in order to provide an abutment or stop against which the finger may be placed to provide for more ready separation or opening of the compartment members, the said member 8 is preferably provided at a point diametrically opposite the extension 9, with a lip 16, and the rim 5 is formed with a notch or recess 17 located opposite the hinge member 12, to receive the said lip 16 when the two sections 1 and 2 are closed. The edge of the wall 3 of the compartment member 1 is also formed with a notch or recess 18 designed to match with the recess 17 for the purpose stated. The lip 16 projects exteriorly of the article when the compartment members are closed as will be apparent by reference to Figs. 1 and 3 of the drawings, and it will be understood that the thumb of one hand may be placed over this lip while the other hand is engaged in swinging open one or the other of the said compartment members. In this manner either compartment member may be more readily opened, and at the same time the supporting member 8 is held in the desired and proper position and against being swung upon its hinge with the said compartment member. As in the case of the extension 9, the lip 16 fills and closes the space between the walls of the matching recess 17 and 18 so that the presence of these recesses does not impair the efficiency of the rim 5 as a sealing means for the case.
- 15 As before stated, the supporting member 8 is provided with means for supporting upon each face thereof a holder for a cosmetic, in the present instance a pad or holder for cakes of rouge and face powder, and this means, as stated, consists of gripping fingers which are struck up from the opposite faces of the plate comprising the member 8, other and longer fingers being also struck up from the opposite face of the
- plate to serve as retaining fingers for the puffs or other applying device employed in connection with the cosmetic. While these two sets of fingers may be relatively arranged in any desired manner, it is preferable that the arrangement be that illustrated in the drawings and most clearly shown in Fig. 4 thereof, as by this arrangement the plate 8 is given a symmetrical appearance and the plate is not weakened at any one portion more than at another by reason of the formation of the openings resulting from striking up the two sets of fingers. In the drawings the gripping fingers are indicated by the numeral 19 and the puff retaining fingers by the numeral 20 and in forming these fingers, substantially radial incisions are made in the plate 8 terminating at their ends near the periphery of the plate, and the material within the bounds of the incisions is struck up from one or the other face of the said plate. Thus the fingers are integrally connected with the plate near the periphery thereof and all of the fingers lie within the bounds of the periphery of the plate. It is preferable that the fingers 19 and 20 be arranged in sets and that the sets be alternately located at the opposite sides or faces of the plate. In other words a set of the fingers comprising one of the fingers 19 and one of the fingers 20 will be struck up so as to extend from one face to the plate 8, the next set of such fingers will be struck up to extend or project from the opposite face of the said plate, and the third set of fingers in the annular series of fingers will be struck up to project from the first mentioned face of the plate, and so on throughout the entire series. While as before stated any desired type of cosmetic holder may be arranged upon each face of the supporting member comprising the plate 8, in the present instance the articles to be held are in the nature of pads 21 each comprising a bottom 22 and an upstanding circumscribing rim 23, each pad supporting and retaining a cake or tablet 24 of some cosmetic such as face powder or rouge. The pads 21 are circular in form, in the illustrated example, and are of such diameter that when disposed with their bottoms or bases 22 facing the sides of the plate 8 and forced into position with their bottoms in contact with the said faces of the plate, the gripping fingers 19 will engage the peripheries of the pads or the rims 23 and the pads will thus be securely anchored to the respective sides of the supporting member. The fingers 19 are relatively short and terminate substantially at the upper edges of the rims 23 of the pads retained thereby, but the fingers 20 are considerably longer than the fingers 19 and they therefore serve, in addition to their main purpose which will be pres-

ently described, as means for guiding or centering the pad 21 as it is forced into engagement between the fingers 19. The fingers 19 and 20 are, of course, resilient and 5 they therefore firmly frictionally engage the rims of the holders or pads 21 after they have been slightly sprung outwardly as the pad is forced into place. Not only do the fingers 19 engage the rims of the respective 10 pads 21, but the fingers 20 at their inner ends also engage the peripheries or rims of the pads and assist the fingers 19 in holding the said pads in place. As heretofore stated and as will be evident by reference 15 to Fig. 2 of the drawings, the fingers 20 project considerably above the powder cakes 24 when the cakes are in position upon the supporting member 8 and therefore when a puff or other applying device indicated by 20 the numeral 25, and substantially of the same diameter as the pad or cake, is disposed upon the face of the cake, its periphery will be engaged by the projecting upper ends of the fingers 20 so as to hold 25 the puff or similar device against lateral displacement. Of course, the fingers 20 do not tightly bind the puff 25 but they serve as stated, as means for preventing displacement of the puff or for maintaining the 30 same in centered position upon the powder cake. Thus the puff cannot become so displaced as to interfere with closing of the compartment members, nor is it likely to be dropped when either compartment member 35 is swung to open position.

If desired, a suitable mirror 26 may be arranged within the closed top of each of the compartment members so that the person using the article will have at hand a 40 mirror at the time of employing either of the cosmetics.

Having thus described the invention, what is claimed as new is:

1. In an article of the class described, a 45 pad and puff supporting member including a plate, relatively short pad gripping fingers projecting from the plate, and relatively long puff retaining fingers also projecting from the plate, the fingers being arranged in an endless series and the bases of all of the fingers touching a common line.

2. In an article of the class described, compartment members, a supporting plate disposed between the open sides of the members, 55 means hingedly connecting the said compartment members and plate, the plate being provided with retaining means upon both of its opposite faces, a cosmetic pad or the like held upon each face of the said plate by the 60 said retaining means, and puff retaining means upon each face of the plate projecting above the surface of the respective cosmetic pad.

3. In an article of the class described, 65 open-sided compartment members, a sup-

porting plate disposed to lie between the open sides of the said members when the latter are closed, of means mutually hingedly connecting said members and said plate, and means upon each side of said plate and carried thereby for supporting an article to be housed within the respective compartment member. 70

4. In an article of the class described, open-sided compartment members, a supporting plate disposed to lie between the open sides of the said members when the latter are closed, means upon each side of said plate and carried thereby for supporting an article to be housed within the respective compartment member, the said plate being provided at a point in its periphery with an outstanding neck provided with oppositely projecting pintle studs, spaced pintle lugs upon one of the compartment members pivotally engaging said studs at the opposite sides of the neck, and spaced pintle lugs upon the other compartment member pivotally engaging said studs outwardly of the first-mentioned studs, whereby the compartment members and said supporting plate are mutually hingedly connected. 80 85 90

5. In an article of the class described, open-sided compartment members, a supporting plate disposed to lie between the open sides of the said members when the latter are closed and to occupy a position substantially equi-distantly spaced from the bottoms of the two members, means mutually hingedly connecting said members 100 and said plate, means upon each side of said plate and carried thereby for supporting an article to be housed within the respective compartment members, and a finger piece projecting from the periphery of the said plate between and beyond the meeting peripheries of the open sides of the compartment members, whereby, by grasping either of said compartment members and said finger piece, the plate may be retained in position closing the said compartment member while the other compartment member is 105 swung to open position.

6. A double compartment powder-box comprising a lower shell providing one compact-receiving compartment, an upper shell providing the other compact-receiving compartment, a hinge means pivotally interconnecting said shells so that the same may be mutually closed one upon another, said 115 lower shell having an inwardly off-set vertical flange portion adapted to telescope into the mouth of the upper shell when said shells are closed together, and a partition member pivotally associated with said hinge 120 means to extend between the compartments and within said shells when the latter are closed together. 125

7. A double compartment powder-box comprising a lower shell providing one com- 130

pact-receiving compartment, an upper shell providing the other compact-receiving compartment, a hinge means pivotally interconnecting said shells so that the same may be 5 mutually closed one upon another, said lower shell having an inwardly off-set vertical flange portion adapted to telescope into the mouth of the upper shell when said shells are closed together, a partition member 10 pivotally associated with said hinge means to extend between the compartments of said shells when the latter are closed together, and means upon the partition member adapted to engage and hold powder and 15 rouge compacts respectively in said compartments.

8. In an article of the class described, compartment members, a supporting member comprising a plate located between the

open sides of the compartment members, 20 means hingedly connecting the compartment members with each other and both with the same supporting plate, and article retaining means upon each face of the supporting plate. 25

9. In an article of the class described, compartment members, one of said members having a rim to fit within the open side of the other member when the members are closed, a supporting plate positioned to lie 30 within the rim when the compartment members are closed, means hingedly connecting the compartment members with each other and with the said supporting plate, and article retaining means upon each face of the 35 supporting plate.

In testimony whereof I affix my signature.
WILLIAM G. KENDALL. [L. S.]
